SELF-LUBRICATING AND COLORING
PROJECTILE

Joseph Schreib, Baltimore, Md.

Application June 5, 1943, Serial No. 489,743

2 Claims. (Cl. 102—93)

This invention refers to ammunition and more particularly to the construction of projectiles used in cannons, guns or rifles. It has among its objects to provide a projectile that is self-lubricating; that will automatically lubricate the barrel of the gun it is fired from; and which will have an arrangement for identifying itself by distinctively marking the target it is used against. A further object is to provide the projectile with a novel type of rifling band designed to provide lubricant and feed it through spaces provided in same in such a manner as to improve the cutting of the thread on the band as it passes through the rifling. Also to have this rifling band furnish the means for identifying the ammunition it is used with.

Other objects will become apparent as the invention is more fully set forth.

While various arrangements have been provided for lubricating the barrel of a gun used for firing projectiles, such have been limited to superficial treatment of the surfaces frictionally and mechanically engaging with one another, and the employment of a lubricant external to the projectile. This is usually called a hot dip process or modifications thereof. This invention avoids this process. In this invention the structure for containing the lubricant is considered paramount, and this consists of specially formed rings made to contain the lubricant and exude it to the rifling ring where it will lubricate the latter for rifling action and antifriction results as it passes through the barrel under fire. The rings are preferably made with dove-tailed parts to engage and hold in grooves in the projectile, and the back portions of the rings formed to hold a suitable lubricant and a coloring indicator adapted to exude out of the rings as the propelling pressures force the projectile through the rifle barrel of a gun. The purpose of the coloring indicator is to provide a definite method of identifying a projectile or the gun it is used with. This is particularly valuable in keeping track of results, which is not practical in other forms of ammunition.

In the drawing, which illustrates an example of a projectile embodying this invention:

Figure 1 is a side elevation partly in section, of a projectile upon which are mounted rifling bands embodying this invention;

Figure 2 is an end elevation of Figure 1; and

Figure 3 is an enlarged sectional view of the rifling band and projectile shown in Figure 1.

Similar reference characters refer to similar parts throughout the drawing.

In the drawing, a projectile 1 of conventional form is milled or cut at 2 with peripheral grooves having a dove-tail cross-section as indicated at 3. The bottom 4 of the grooves is preferably flat and straight. The grooves are filled with rifling rings 5 provided with convexedly curved peripheral faces 13 made up of many relatively short sections cut slantingly in a direction away from that of the rifling of the gun barrel they are to be fired from. These sections are forced into place in the grooves 3. The spaces 6 between the sections are very minute and serve to permit very limited amount of lubricant 7 to pass out between them. In addition the sections have holes or passages 8 through them for the radial expulsion of the lubricant therethrough. The bottom portion and surfaces 9 of the rings 5 are enlarged to fit snugly in the dovetailed portions 3 of the grooves 2. A series of lubricant reservoirs 10 are formed in the bottom and open out internally against the bottom surface 4 of the grooves 3 and through passages 8. The passages 18 are arranged to contain coloring indicator 11 and to flow out radially away from the projectile external surface. The passages are blanked off at 20.

The operation of firing the projectile from the barrel of a gun is as follows: The explosive charge presses against the back surface 12 of the bullet and forces it forward. This presses the first ring 5 into contact with the rifling groove of the barrel. The ring on the projectile is relatively soft and moves forward therewith through the rifling groove and takes on a helical formation conforming with the pitch of the rifling. The ring and projectile rotate together in the rifling as they are forced forward through the barrel. Later the second ring comes into contact with the rifling groove and is cut likewise. The second ring accumulatively cooperates with the function of the first ring and rifling groove and gives the projectile a continued and more forceful rotation. As the rifling ring 5 is forced through the barrel, its convexedly curved external surface 13 is pressed inwardly by the surface of the barrel and the high pressure of the explosive gases therein. This presses on the body of the ring and makes it exude some of its lubricant against the back 4 of the groove, and thence through the passages 8 and spaces 6 to the surface of the ring and the rifling groove. This lubricates the surfaces and reduces the frictional resistance of the projectile and enables the rifling groove to cut a surface rifling screw thread thereon, more readily.

When the projectile has passed out of the gun and reached its target, it tears a hole in same and in doing so acts on the expanded coloring indicator to shake and force it out externally from the ring, to color the target.

The type of lubricant usable in this invention is subject to variations and improvements as time passes and is therefore not accentuated as a part of this application, since specific protection is not sought in that regard. However, the type of lubricant considered suitable is that of a graphite base carried in a vehicle that leaves no residue or ash after discharge of the projectile, such as those of an alcohol nature. The colored indicator is preferably of an earthy nature carried in a high temperature greasy vehicle. The color of the indicator can be varied to suit the ammunition used and to identify where it has struck. The same color is preferably painted on the nose 16 of the projectile to identify the indicator used with it.

While but one general form of the invention is shown in the drawing and described in the specifications, it is not desired to limit this application for patent to this particular form or in any other way otherwise than limited by the scope thereof as it is appreciated that other forms of construction could be made that would use the same principles and come within the scope of the appended claims.

Having thus described the invention, what is claimed is:

1. A projectile of the class described comprising in combination, a projectile body of conventional form and material having dovetailed 35

grooves formed concentrically about the axis thereof in the peripheral portion, a ring of metal adapted to conform with the rifling of a gun in which it is fired and projected above the peripheral surface of the said body to adapt itself thereto, said ring being of conventional material suitable for the purpose and having its inner portion formed into a dovetail contour with the said grooves in the body, said ring having minute interstices and spaces formed therein with lubricant forced therein adapted to exude therefrom when used in the rifling of a gun during its travel therethrough and passages in said ring for holding coloring matter for marking the target.

2. A projectile of the class described comprising in combination, a projectile body of conventional form and material having dovetailed grooves formed concentrically about the axis thereof in the peripheral portion, a ring of metal adapted to conform with the rifling of a gun in which it is fired and projected above the peripheral surface of the said body to adapt itself thereto, said ring being of conventional material suitable for the purpose and having its inner portion formed into a dovetail contour to conform with the said grooves in the body, said ring having minute interstices and spaces formed therein with lubricant forced therein adapted to exude therefrom when used in the rifling of a gun during its travel therethrough and passages in said ring for holding coloring matter for marking the target, and tapered portions in said interstices in the inner portion thereof for forming a reservoir for the lubricant to accumulate.
